UNITED STATES PATENT OFFICE.

CHARLES AUGUSTE ORLEANS, OF NEW ORLEANS, LOUISIANA.

DESIGN FOR A MONUMENT.

SPECIFICATION forming part of Design No. 37,198, dated October 25, 1904.

Application filed August 9, 1904. Serial No. 220,123. Term of patent 7 years.

To all whom it may concern:

Be it known that I, CHARLES AUGUSTE ORLEANS, a subject of the King of Great Britain and Ireland, residing at New Orleans, parish 5 of Orleans, and State of Louisiana, have invented a new, original, and ornamental Design for a Monument, of which the following is a specification, reference being had to the accompanying drawing, forming a part thereof.

10 The figure shows the front and one side of the monument in perspective, showing my new design.

What I claim as new, and desire to secure by Letters Patent, is—15 The ornamental design for a monument as shown.

CHARLES AUGUSTE ORLEANS.
